UNITED STATES PATENT OFFICE.

ANDREW BOLTON, DECEASED, LATE OF MANCHESTER, ENGLAND, BY ELIZABETH ANNE BOLTON, EXECUTRIX, OF MANCHESTER, ENGLAND.

STEAM-SUPERHEATER.

1,073,844.

Specification of Letters Patent. Patented Sept. 23, 1913.

Application filed March 19, 1913. Serial No. 755,440.

To all whom it may concern:

Be it known that ANDREW BOLTON, who was a subject of the King of Great Britain and Ireland, and a resident of 49 Deansgate, 5 Manchester, in the county of Lancaster, England, but is now deceased, and whose executrix is ELIZABETH ANNE BOLTON, a subject of the King of Great Britain and Ireland, and resident of Holly Lodge, Demesne Road, 10 Manchester, S. W., England, did invent a certain new and useful Improvement in Steam-Superheaters, of which the following is a specification.

This invention relates to steam superheaters for locomotives or locomotive or other type boilers, its object being to provide an improved form or arrangement of superheater, which while it provides an efficient superheating action upon the steam passing therethrough, is economical to make and simple to fit in position.

Referring to the two accompanying sheets of explanatory drawings:—Figure 1 is a sectional elevation of a superheater constructed in accordance with his invention and applied to a locomotive. Fig. 2 is an end elevation partly in section of said superheater.

The same reference letters in the two views 30 indicate the same parts.

He forms the superheating elements from a number of Field tubes *a* extending into some or all of the boiler smoke tubes *b*, in a known manner. The said tubes *a* are supported by 35 a plurality of headers *c* suspended from the saturated steam inlet and superheated steam outlet pipes or connections *d* and *e* respectively. Each header has a division plate or partition *f* therein to receive the inner elements of the Field tubes and a further division 40 piece *g* extending between the steam inlet and outlet ports *d*, *e* for directing the steam from the inlet through one portion of the Field tubes, the said steam being then directed through the remainder of said tubes

and to the outlet connection *e* at the other side of the division piece *g* referred to. The large or outer elements of the Field tubes are secured to the outer wall of the header. The inlet and outlet ports of the header are adjacent to one another, but he preferably makes the saturated and superheated steam connections *d*, *e* leading to or from said header, separate from one another so as to allow for relative expansion.

Each header *c* is secured in place by bolting or otherwise and can be readily removed from position without interfering with the adjacent headers.

If desired, he may make the tube plate *g*¹ 60 of each header detachable from the latter so that the outer elements of the Field tubes can be expanded therein.

The diaphragm or division plate *f* into which the inner elements of the Field tubes 65 are secured, may be of arched formation and the header itself preferably tapers off toward its lower end as shown. The division wall between the inlet and outlet sides of the header also preferably inclines toward 70 the vertical wall of the superheater before joining the diaphragm aforesaid into which the inner elements of the Field tubes are secured. The arrangement of parts gives a compact design or construction of superheater. The Field tubes *a* are preferably 75 arranged in vertical rows as shown, each row being supported by one header. One or more tubes is or are inserted within each of the smoke tubes.

His superheater may be employed in connection with marine or other types of boiler.

Having now described his invention what he claims as new and desires to secure by Letters Patent is:—

In steam superheaters, in combination, a plurality of headers, a saturated steam inlet and a superheated steam outlet to each of said headers, a division wall extending between said inlet and outlet, a diaphragm 90

extending across said header and joined by the division wall at a point midway between the ends of the diaphragm, open ended tubes supported at one end by said diaphragm, 5 some of said tubes communicating with the steam inlet and the remainder with the steam outlet, and tubes closed at one end supported around the open ended tubes by said header, substantially as described.

In testimony whereof I affix my signature 10 in the presence of two witnesses.

ELIZABETH ANNE BOLTON,
*Executrix of the estate of Andrew Bolton,
deceased.*
